(57) **CLAIM**

The ornamental design for a lap pad for inversion apparatus, as shown and described herein.

DESCRIPTION

FIG. 1 is a front perspective view of a lap pad for inversion apparatus showing our new design;

FIG. 2 is a top view thereof;

FIG. 3 is a bottom view thereof;

FIG. 4 is a rear view thereof;

FIG. 5 is a front view thereof;

FIG. 6 is a first side view thereof;

FIG. 7 is a second side view thereof; and,

FIG. 8 is a front perspective view, showing the lap pad for inversion apparatus in use.

The portions of the lap pad for inversion apparatus shown in broken lines form no part of the claimed design.

Broken lines in FIG. 8 showing environment form no part of the claimed design.

1 Claim, 8 Drawing Sheets
